LOW NOISE ELECTRON GUN

Malcolm R. Currie, Beverly Hills, Calif., assignor to Hughes Aircraft Company, Culver City, Calif., a corporation of Delaware

Application December 3, 1957, Serial No. 700,440

9 Claims. (Cl. 315—31)

This invention relates to electron beam devices, and particularly to a low noise electron gun for such devices.

In electron discharge devices, especially in amplifiers such as traveling-wave tubes, backward-wave tubes and klystrons, limitations on usefulness are frequently imposed by its own inherent noise generation which the tube may amplify to a level which is detrimental to the other functions of the tube. The conventional measure of this noise is designated "noise figure" and is defined as the signal to noise ratio at the input of the device divided by the signal-to-noise-ratio at the output. This is particularly true in traveling-wave tube devices, and especially true in backward-wave amplifiers. A voltage tunable backward-wave amplifier is frequently considered desirable for use in radar receivers. In such a utilization, maximum range of the radar system is determined by the noise figure of the tube; thus, it is advantageous to employ tubes having the lowest possible noise figure. Many other advantages of a low noise device will readily suggest themselves to those skilled in the art.

Low noise electron guns have heretofore usually consisted essentially of a diode region, that is, an emitting cathode and accelerating anode followed either by a series of accelerating anodes or a series of drift tubes operated at different potentials. In either case, the purpose of the region beyond the first anode is to minimize and deamplify the noise in the beam. In the first type, this is accomplished as gradually as possible by a change in potential as a function of distance from the cathode. In the latter type, it is accomplished by sudden velocity jumps which tend to minimize velocity fluctuations among the electrons in the stream. In both cases, the initial diode region is designed with considerable effort toward launching the beam in a uniform flow. The resulting beam accordingly has a more or less uniform density across its width. It has previously been considered to be essential, in accordance with the theoretical models utilized, to launch the electrons as smoothly and evenly as possible from the emitting surface. The use of either a distorted potential profile or a nonuniform current density has been regarded as highly harmful to the noise figure of tubes, particularly those employing long electron beams. It has also been considered essential, according to the theoretical models used that a space charge limited type of emission be utilized in order to smooth out current fluctuations in the beam near the cathode. In fact, all accepted prior art theoretical models have assumed a normal Fry-Langmuir potential distribution away from the cathode in order theoretically to minimize reduction in shot current and reduction in velocity fluctuations. These models have lead to the prediction of a generally accepted minimum theoretical noise figure in the range of 5 to 6 decibels which has been approached in practice and has been considered generally to be the best that could ever be attained. (See Proceedings of the I.R.E., vol. 43, pp. 981-991, August 1955, "Minimum Noise Figure of Microwave Amplifiers," by H. A. Haus and F. N. H. Robinson.)

2

A prime object of the present invention is to provide an exceedingly low noise electron gun.

Another object is to provide a low noise electron gun for use in a beam type amplifier device having a noise figure considerably below what has been considered to be the theoretical minimum.

It is another object to provide a low noise electron gun in which the improvement in noise reduction is achieved in the region between the cathode and anode.

10 It is another object to provide a low noise electron gun in which an unique arrangement of potentials and geometry of electrodes about the emitting cathode cause electron beam formation in a manner to obtain an exceedingly large amount of noise reduction.

15 Briefly, these and other objects and advantages of the present invention are achieved in one embodiment by providing an arrangement including an emissive cathode which is immersed in a relatively strong magnetic field which is coincident with the desired path of the electrons.

20 The cathode has an emissive region lying within a short segment along the path. Disposed further along the path and spaced from the emissive region of the cathode is an accelerating electrode having a potential only slightly greater than that of the cathode, while disposed abeam

25 of the emissive region of the cathode and extending both behind and in front thereof is a potential profile-shaping electrode having an inclined surface exposed toward the emitting region or segment and diverging away from the path at a predetermined angle. This profile-shaping electrode is maintained at a direct current potential which is more positive with respect to the cathode than is the accelerating electrode. This arrangement of electrodes and relative potentials produces a potential field having a gradient near the edge of the emitting region or seg-

30 ment of the cathode which has a pronounced radial component which would normally tend to pull electrons toward the profile-shaping electrode. However, the strong axial magnetic field precludes such motion for electrons having the desired velocity, and the electrons are pulled

35 toward the accelerating electrode because of the crossed-field effects.

40 It is to be noted that the electrodes and potentials are arranged so that the electron current is pulled predominantly from that part of the emitting region which

45 is next to the edge of the cathode toward the profile-shaping electrode. This applies to strip cathodes, annular cathodes and conventional planar disc cathodes.

46 The potential profile seen by these edge electrons in the absence of the rest of the beam is unique. It consists of a sharply distorted increase in potential away from the cathode followed by a relatively long region in which the potential is nearly constant or increases only very slowly as a function of distance from the cathode. In this manner, a highly nonuniform current density 50 across the cross-section of the beam is provided which discriminates against undesired velocities, reduces shot current and introduces a statistical correlation between these noise quantities, that is, between shot current and velocity fluctuation. This, then, qualitatively describes 55 the theoretical model upon which the present invention is based.

60 The novel features of this invention, as well as the invention itself, both as to its organization and method of operation, will best be understood from the following description, taken in conjunction with the accompanying drawing, in which like reference numerals refer to like parts, and in which:

65 Fig. 1 is a schematic view, partially in section, of an electron beam device constructed in accordance with the present invention;

70 Fig. 2 is a perspective view of a generalized embodi-

ment of the low noise electron gun of the present invention;

Fig. 3 is a view of a sheet beam-forming electron gun embodiment;

Fig. 4 is a view of a generalized cylindrical embodiment of the electron gun of the present invention;

Fig. 5 is a view, partially in section, of a modified cylindrical version of the electron gun of the present invention;

Fig. 6 is a sectional view of a hollow cylindrical beam-forming embodiment of the electron gun of the present invention;

Fig. 7 is a diagram showing in greater detail the geometrical relationships of certain features of the electron gun of the present invention;

Fig. 8 is a pictorial graph plotting relative current density across the emissive surface of a cathode of an electron gun of the present invention;

Fig. 9 is a pictorial graph plotting relative electron current density across the emissive surface of a cathode of a hollow electron beam of the present invention;

Fig. 10 is a graph plotting a typical potential profile of an electron gun of the present invention in which potential in volts is plotted as a function of inches from the cathode edge along the axis of the tube.

Referring now to the drawings with more particularity, Fig. 1 illustrates an embodiment of the present invention combining a low noise electron gun with a particular electron beam amplifying device, the particular example chosen being a traveling-wave tube amplifier 12. A glass envelope 14 includes an enlarged diameter portion 16 at its lefthand extremity connected to an elongated portion of lesser diameter 18. Sealed to the righthand extremity of the elongated portion 18 is a collector electrode 20. Disposed along substantially the length of the elongated portion 18 is a slow-wave structure 22 which is terminated on either end by a matching ferrule 24. Coupled to the input or lefthand end of slow-wave structure 22 is a coaxial transmission line 26, the inner connector 28 thereof having a helical extension 30 which is wrapped around envelope 14 in a manner to provide a contrawound helical transducer for launching traveling waves onto slow-wave structure 22. Similarly, an output coaxial transmission line 32 is coupled to the output end of slow-wave structure 22 in a manner to couple traveling wave signals off from slow-wave 22 and transmit them to a utilization device, not shown.

Disposed within the enlarged portion of the envelope 14 is an electron gun 34 which comprises in this particular example a cylindrical cathode 36 having a substantially planar emissive surface 38 at its righthand end. Cathode 36 is heated in a conventional manner by a heating electrode 40. A profile-shaping electrode 42 is disposed about the cathode 36 in a manner to substantially surround emissive surface 38 and extends both fore and aft of the emissive surface. The profile-shaping electrode 42, along with other elements of the gun 34, may be supported by a set of dielectric rods 44 which maintain axial alignment and mechanical rigidity. Disposed further along the axis of the tube 12 to the right of the profile-shaping electrode 42 may be placed a series of accelerating electrodes maintained usually at progressively more positive potentials. Throughout this description only one or two such electrodes are shown for purposes of simplifying the discussion. The first accelerating electrode 46, in this particular example, is an annular member having an opening 48 of sufficient diameter to permit passage of an electron stream emitted by the cathode 36. Of similar geometry, and spaced further along the tube 12, is a second accelerating electrode 50 which has geometry similar to that of the electrode 46. Both accelerating electrodes are also supported on the dielectric rods 44. The cathode 36 is maintained at a negative potential by a source of potential 52, the negative terminal of which may be connected to the cathode 36. At an

appropriate tap, the heating electrode 40 is also connected to the source 52. The first accelerating electrode 46 is maintained at a positive potential with respect to the cathode by a connection to an appropriate tap, as shown, and to the source 52. The profile-shaping electrode 42 is connected to the source 52 at a next more positive tap. The second accelerating electrode 50 is maintained next more positive by an appropriate tap, also to the source 52. Slow-wave structure 22 may be maintained next more positive, as shown, by connecting it to ground potential through an isolating resistor 54.

Surrounding substantially the entire length of the traveling-wave tube 12 is a focusing magnet 56, which may be a solenoid, as shown, and which is energized by a source of potential 58. The magnet 56 extends over the electron gun 34 and immerses it in a strong axial constraining magnetic field so that electrons which would tend to be drawn toward the profile-shaping electrode 42 are instead constrained to flow in the axial direction along the length of the traveling-wave tube 12 within the slow-wave structure 22. The electrons are eventually intercepted by the collector electrode 20 which dissipates their kinetic energy and conducts them to ground through a source of potential 60. The source 60 is connected with its positive terminal to the collector 20 so that secondarily-emitted electrons will not drift backwardly into the interaction region of slow-wave structure 22 and cause added shot noise, or other deleterious effects.

Fig. 2 illustrates generally the geometrical relationships which are considered fundamental in an explanation of the structure of the electron gun of the present invention. The cathode 62 has an emitting surface 64 lying within an axially short segment 66 along the axial predetermined path for an electron stream 68. The cathode 62 is maintained at a reference potential of zero volts. A profile-shaping electrode surface 70 is disposed transversely from the path and extends axially both behind and in front of the emissive segment 66. The surface 70 is inclined in a manner to be exposed toward the emissive segment 66 and diverges along the direction of the electron stream 68. The profile-shaping electrode surface 70 is maintained at a direct current potential V_2 of a few volts positive with respect to the cathode 62 which is designated as being of potential V_0 (as seen in Fig. 2) of the cathode 62 and the profile-shaping electrode surface 70 is an accelerating electrode 72 which is placed substantially perpendicularly to the electron stream 68 and is closely adjacent thereto. The accelerating electrode 72 is maintained at a direct current potential V_1 which is intermediate to those of the cathode 62 and the profile-shaping electrode surface 70. By intermediate is meant that the potential V_1 is somewhere between the other two potentials. The entire structure of Fig. 2 is immersed in a strong axial magnetic field which is parallel to the electron stream 68.

Referring now to Fig. 3, there is shown a sheet beam-forming electron gun in which a cathode 74 has an emissive surface 76 which is included within a short axial emissive segment 78 of the cathode 74. A profile-shaping electrode 80 is disposed symmetrically above and below the emissive segment 78 and has inclined profile-shaping surfaces 82 which are exposed toward the emissive segment 78 and diverge along the path of the electron stream 84. The surfaces 82 are contiguous to the cathode 74 and extend both fore and aft of the emissive segment 78. Disposed to the right of profile-shaping electrode 80 is an accelerating electrode 86 which is oriented perpendicularly to the path of electron stream 84 and is contiguous thereto. The cathode 74 is maintained at a direct current potential of zero, designated as V_0 . The accelerating electrode 86 is maintained at a direct current potential V_1 which is slightly positive, and the profile-shaping electrode 80 is maintained at a direct current reference potential which is next more positive and which is designated as V_2 . Again, the entire configuration of

Fig. 3 is immersed in a strong axial magnetic field designated H.

Referring to Fig. 4, there is shown a cylindrical embodiment of the low noise electron gun of the present invention. A cylindrical cathode 88 is axially aligned with the path of an electron stream 90 and is maintained at a direct current reference potential V_0 which is equal to zero. The cathode 88 has an emissive surface 92 at its righthand extremity which is oriented substantially perpendicularly to the path of the stream 90. Disposed concentrically about the emissive surface 92 is a profile-shaping electrode surface 94 having the form of a frusto-conical surface of revolution, the determining planes of which lie respectively fore and aft of and parallel to the emitting surface 92. Disposed to the right along the path of electron stream 90 is an accelerating electrode 96 having an inner circular aperture which is concentric with the electron stream, and which is perpendicularly oriented with respect thereto. The cathode 88 is maintained at a direct current reference potential V_0 of zero volts, the accelerating anode 96 is maintained at a potential V_1 which is slightly positive with respect to the cathode, and the profile-shaping electrode 94 is maintained next more positive at a potential designated V_2 . The entire configuration is immersed in a strong axial magnetic field H.

Referring now to Fig. 5, there is shown a different one of a cylindrical beam gun including a cylindrical cathode 98 having an emissive end 100 lying within an axially short emissive segment 102. A profile-shaping electrode 104 is disposed perpendicularly to the axis of the cathode 98 and has a coaxial frusto-conical aperture 106 disposed about the cathode 98 and which extends both fore and aft of the emissive segment 102. The frusto-conical surface of aperture 106 is adjacent to the emissive segment 102 and diverges in the direction of the electron stream. The aperture 106 may comprise also surfaces 108 and 110 which are in this particular example cylindrical surfaces concentric with the axis of the cathode 98. Disposed to the right of the profile-shaping electrode 104 is an accelerating electrode 112 which has a circular aperture 114 concentric with and disposed contiguously to the electron stream emitted by the cathode 98. The cathode 98 is maintained at a direct current potential V_0 equal to zero volts, the profile-shaping electrode 104 is maintained at a direct current potential V_2 which is a few volts positive with respect to the cathode, and the accelerating electrode 112 is maintained at a direct current potential V_1 which is intermediate the potentials V_0 and V_2 . The cathode 98, the profile-shaping electrode 104, and the accelerating electrode 112 are immersed in a strong axial constraining magnetic field H.

Referring to Fig. 6, there is shown a low noise electron gun which produces a hollow annular electron stream 116. An annular cathode 118 is maintained at a direct current reference potential V_0 equal to zero volts and is immersed in a strong axial constraining magnetic field H. A profile-shaping electrode 120 having a coplanar inner portion 122 is disposed perpendicularly to the axis of the cathode 118 and is axially oriented so as to extend both forwardly and rearwardly of the right hand emitting end 124 of the cathode 118. The profile-shaping electrode 120 has a circular aperture which comprises a frusto-conical surface of revolution 126 disposed concentrically about and radially contiguous to the cathode 118. The profile-shaping electrode portion 122 comprises an outer frusto-conical surface of revolution which is concentric with the cathode 118 and, as previously mentioned, is coplanar with profile-shaping electrode 120. The frusto-conical surfaces of profile-shaping electrode 120 and profile-shaping electrode portion 122 each diverge along the direction of the electron stream 116 at the same angle of divergence. Disposed perpendicularly to the electron stream 116, to the right of the profile-shaping electrode 120, is an accelerating electrode 128 which has an annular aperture 130 concentric with and adjacent

radially to the electron stream 116. Disposed further yet to the right (as seen in Fig. 6) is a second accelerating electrode 132 which is similarly oriented and of similar geometry with respect to the accelerating electrode 128. One or more additional accelerating electrodes may also be utilized here.

Referring now to Fig. 7, there is shown in more detail the dimensions and relationships of a low noise electron gun constructed in accordance with the invention. A cathode 134 is disposed along the axis of an electron stream 136 and has an emissive end portion 138 which is substantially planar and lies substantially perpendicularly to the axis of electron stream 136. The cathode 134 has a diameter or transverse dimension d and is maintained at a direct current potential V_0 equal to zero volts. A profile shaping electrode 140 is disposed about and lies between a transverse plane 142 which is aft of emitting portion 138 by a distance a , and a transverse plane 144 which is forward of the emitting portion 138 by a distance designated b . The surface of the profile-shaping electrode 140 exposed toward the emissive end portion 138 is inclined at an angle β from the axis of the cathode 134. The edge of the profile-shaping electrode 140 determined by plane 142 is spaced from the cathode 134 by a distance designated e . Spaced forwardly from the plane 144 by a distance c is an accelerating electrode 146 which is disposed symmetrically above and below, or around, the electron stream 136 and is maintained at a direct current potential V_1 . The profile-shaping electrode 140 is maintained at a direct current reference potential of V_2 . Some typical ranges for the dimensions and voltages for optimum noise reduction in a practical embodiment, constructed substantially in accordance with the geometry of Fig. 7, are:

- 35 a—Between .005 inch and .200 inch;
- b—Between .005 inch and .060 inch;
- c—Between .020 inch and .100 inch;
- d—Between .005 inch and .200 inch;
- e—Between .003 inch and .070 inch;
- 40 β —Between 30° and 75° ;
- V_0 —zero volts;
- V_2 —Between +3 and +20;
- V_1 —at or below V_2 .

45 These dimensions and voltage ranges are not given as being the limits for their respective parameters, but are merely given as empirical numbers which have proven to be especially successful in achieving noise reduction in electron guns constructed in accordance with the present invention.

50 Referring now to Fig. 8, there is shown a pictorial graph of relative electron current density on the horizontal scale versus position across the emitting surface 150 of a typical cathode 152, as is shown by the curve 148. The current is at a maximum near the edge of the cathode 55 and decreases to a minimum in either direction away from the edge.

55 Fig. 9 shows a plot similar to that of Fig. 8 in which a curve 154 plots relative electron current density horizontally versus radial position across the emissive surface 156 of an annular beam-forming cathode 158. The profile-shaping electrodes are not shown in either of Figs. 8 or 9, but the electron current density plots shown exist both by virtue of a profile-shaping electrode surface such as shown in the other figures which is symmetrically disposed about the emitting portions of the cathodes schematically shown in Figs. 8 and 9 and by virtue of the unique potential distribution. Again, in Fig. 9 it is seen that the electron current density is greatest near the edges of the cathode 158 and decreases to a minimum in either radial direction therefrom.

60 Referring to Fig. 10, there is shown the nature of the potential profile achieved by the various embodiments of the low noise electron gun of the invention. Plotted on the vertical axis is potential in volts versus thousandths

of an inch distance from the emitting surface on the horizontal scale. The curve 160 represents the potential which would be seen by an electron emitted near the edge of a cathode such as the cathode 134 of Fig. 7. The curve 160 represents the potential seen by such an electron in the absence of space charge effects from the rest of the electron beam. The particularly pertinent features to be noted are the steep initial gradient represented by dotted line 162 which illustrates the gradient tending to initially accelerate edge-emitted electrons. The long substantially gradient-free drift region between 10 and 70 on curve 160 represents the long drift region experienced by the emitted electrons.

A curve 164 represents the potential profile experienced by an edge emitted electron in the presence of the rest of the electron beam. The profile of the curve 164 is substantially depressed from that of the curve 160 and represents that electrons in the beam remain for a longer period of time in a region of exceedingly low potential at which the thermal velocity spread in the beam is comparable to the magnitude of the direct current potential.

In the operation of the electron beam device of Fig. 1 microwave energy is delivered to the traveling-wave tube 12 along coaxial transmission line 26 if the tube is being operated as a forward-wave device, or along coaxial transmission line 32, if the tube is being operated as a backward-wave amplifier device. In any event, microwave energy is propagated along the helix 22 and is caused to interact in a well-known manner with an electron beam projected from the electron gun 34 along the axis of the tube contiguous to the helix 22. The microwave energy in the form of a traveling wave having experienced interaction with the electron stream normally in a manner to achieve amplification, is then coupled off of the helix 22 by the appropriate helical transducer and transmitted to a utilization device, not shown.

Referring to the operation of the electron gun 34, the cathode 36 is heated by current flowing through coil 40 causing thermal emission of electrons from the emissive area 38. The surrounding profile-shaping electrode 42 being maintained at a positive potential tends to cause electrons to tend to be pulled radially outward toward it. However, the strong magnetic constraining field maintained by the solenoid 56 causes the emitted electrons to spiral and travel forward toward the slightly positive accelerating electrodes 46 and 50. It is to be noted that the inclined surface of the profile shaping electrode maintained at a higher potential than the first accelerating electrode as illustrated in each of Figs. 1-7 is considered to be the preferred arrangement for providing the long drift profile of Fig. 10. Figs. 2 and 3 illustrate embodiments which provide the desired potential profile along a strip, or rectangular beam. The inclined surface is clearly shown as being exposed toward the emissive portion of the cathode and diverging from the electron path. The strong axial magnetic field constrains the electrons to flow in the forward direction in spite of the transverse electric field.

Figs. 4, 5 and 6 illustrate cylindrical beam forming embodiments in which again the orientation of the inclined surface of the potential profile shaping electrode is clear. These figures represent embodiments which are particularly useful in traveling wave tubes such as backward-wave amplifiers. In each of these figures the inclined surface of the profile shaping electrode diverges from the path of the beam and is maintained at a potential which would tend to pull the electrons outwardly from the edge of the cathode but for the strong constraining effect of the magnetic field H which forces them to spiral instead toward the apertures of the accelerating electrodes.

The potentials utilized for the profile-shaping electrode 42 and the accelerating electrodes as well as their geometry are such as to provide the long drift region depicted by the graph of Fig. 10. Hence, a number of factors affecting noise reduction within the cathode-anode region

come into play. Firstly, there appears to be a considerable reduction in velocity fluctuations; secondly, a reduction in shot current, electron-current fluctuations, is achieved; and thirdly, a strong statistical correlation between the remaining current density fluctuations versus electron velocity fluctuations appears to take place. As discussed previously, prior art techniques aimed at achieving the lowest possible noise in an electron gun have consistently been based on the assumption that the most even flow possible from the emissive surface was necessary. Needless to say, it has not been disclosed that it would be desirable to greatly distort both the potential profile existing in the cathode-anode region, as well as the current density distribution across the width of the electron beam in order to achieve noise reduction. In fact, great effort was expended in minimizing such distortions. It is to be noted, in accordance with the theoretical model here chosen, as previously discussed, that it is considered that these distortions contribute to the noise reduction which has been found to exist in electron guns constructed in accordance with the present invention. It is to be noted further that prior art techniques discussed above in the introduction, in accordance with the theoretical models there used have predicted a theoretical minimum noise figure of approximately 6 decibels, while electron guns of the present invention which disregard conventional theory and practice readily achieve noise figures of the order of 3 decibels.

Referring again to Fig. 10, although the curve 160 has been measured and found to exist substantially as shown and in fact represents a solution of the Laplace equation, the curve 164 which represents a practical solution of the Poisson equation is not so well understood. It is substantially depressed due to space charge effects of the emitted electrons and presumably electrons emitted from near the edge of the cathode experience the gradient indicated by the dotted line 162. Undoubtedly, the noise reduction is achieved within the relatively very long drift region between the numbers 10 and 80 on the abscissa. The usefulness of the present invention is not intended to be contingent on this explanation, the purpose of the explanation being merely to show some of the differences between the type of gun here utilized and the prior art geometrical and potential configurations.

What is claimed is:

1. A low noise electron gun for projecting a stream of electrons in a selected direction along a predetermined path comprising: an emissive cathode; means for providing a constraining magnetic field about said cathode in the selected direction along said path; a profile-shaping electrode contiguous to said cathode and disposed at right angles thereto with respect to said direction and having a surface exposed toward said cathode and toward said direction at an exposure angle between said direction and said right angles; an accelerating electrode disposed about said stream and positioned along said path at a point farther from said cathode, said cathode being at a reference potential of zero volts, said accelerating electrode being at a potential positive with respect to said cathode, and said profile-shaping electrode being at a potential positive with respect to said accelerating electrode, whereby electrons are emitted from said cathode and are constrained by said magnetic field to flow in said direction through a substantially potential free region toward said accelerating electrode.

2. A low noise electron gun for providing an electron beam along a predetermined lineal path comprising: an emissive cathode; means for providing a magnetic field along said path and about said cathode; a profile-shaping electrode disposed adjacent to said cathode at right angles thereto with respect to said path, said profile-shaping electrode having a surface inclined toward said cathode and toward said direction, said surface forming an acute angle with said path, said cathode being at a reference potential of zero volts, said accelerating electrode being

at a potential positive with respect to said cathode, said profile-shaping electrode being at a potential positive with respect to said accelerating electrode, whereby electrons are emitted from a portion of said cathode lying toward said profile-shaping electrode and are constrained by said magnetic field to flow in said direction through a substantially potential free region toward said accelerating electrode.

3. A low noise electron gun for producing a stream of electrons along a predetermined path comprising: an emissive cathode disposed at one end of said path; means for providing a magnetic field through said cathode and along said path; an accelerating electrode disposed along said path and spaced from said cathode; a profile-shaping electrode disposed adjacent to and a beam from said cathode and having a surface inclined toward said cathode and said path at an angle with said path of 30 to 75 degrees and extending forward from said cathode by .005 to .060 inch, said cathode being at a reference potential of zero volts, said accelerating electrode being at a potential positive with respect to said cathode, said profile-shaping electrode being at a potential positive with respect to said accelerating electrode, whereby electrons are emitted from said cathode and are constrained by said magnetic field to flow in said direction through a substantially potential free region toward said accelerating electrode.

4. A low noise electron gun for projecting a stream of electrons along a predetermined path comprising: an emissive cathode having an emissive surface lying within a short axial segment along said path; a profile-shaping electrode disposed transversely to said path and having an axial thickness which is greater than the length of said axial segment and which extends both fore and aft of said axial segment of said path, said profile-shaping electrode having an inclined surface exposed toward said axial segment, said exposed surface forming an acute angle with said path; and an accelerating electrode disposed also transversely to said path and forward of said emissive axial segment of said cathode, said cathode being maintained at a direct current reference potential of zero, said accelerating electrode being maintained at a direct current potential which is positive with respect to said cathode and said profile-shaping electrode being maintained at a direct current potential which is positive with respect to said accelerating electrode.

5. A low noise sheet-beam electron gun for projecting a stream of electrons along a predetermined path comprising: a rectangular emissive cathode having a planar surface disposed transversely to said path and included within a short axial segment thereof, at least a portion of said cathode within said axial segment being emissive; a profile-shaping electrode disposed parallel to said planar surface contiguous to said cathode and having an axial thickness which is greater than the axial length of said axial segment, said profile-shaping electrode having an inclined planar surface exposed toward said axial segment and toward the direction of said path; an accelerating electrode disposed substantially parallel to said profile-shaping electrode contiguous to said path and spaced from said axial segment; and means for providing a relatively strong axial magnetic field throughout the region defined by the rear of said profile-shaping electrode and the front of said accelerating electrode, said cathode being maintained at a direct current reference potential of zero, said accelerating electrode being maintained at a direct current potential which is positive with respect thereto and said profile-shaping electrode being maintained at a direct current potential positive with respect to said accelerating electrode.

6. A low noise electron gun for projecting a stream of electrons along an axial path in a predetermined direction comprising: a cylindrical emissive cathode having a substantially planar end portion perpendicular to said axial path which is included within an axially short emitting

5

segment of said cathode; a profile-shaping electrode disposed concentrically about said emissive segment and extending fore and aft thereof with respect to said path, said profile-shaping electrode comprising a frusto-conical internal surface of revolution exposed toward said emitting segment and diverging toward said direction; an accelerating electrode comprising a transverse sheet having an aperture concentric with said path disposed transversely to said path and spaced from said profile-shaping electrode; and means for providing an axial constraining magnetic field throughout the region defined by said profile-shaping electrode and said accelerating electrode.

7. A low noise electron gun for providing a cylindrical beam of electrons along an axial path in a predetermined direction comprising: a cylindrical cathode member having an emissive end portion including a planar end and an emissive cylindrical surface adjacent thereto within an axially short emitting segment; a profile-shaping electrode concentric with said cathode disposed between first and second planes which are transverse to said axial path, said first plane lying aft of said emitting segment and said second plane lying forward of said emitting segment and having a frusto-conical internal surface of revolution disposed symmetrically about said axial path extending between said planes and diverging along said axial path; an accelerating electrode comprising a plane transverse to said path spaced from said profile-shaping electrode and having a circular aperture concentric about said axial path; and means for providing an axial constraining magnetic field extending throughout the region between said first plane and said accelerating electrode, said cathode being maintained at a direct current reference potential of zero volts, said accelerating electrode being maintained at a direct current potential which is positive with respect thereto and said profile-shaping electrode being maintained at a direct current potential which is positive with respect to said accelerating electrode.

8. A low noise electron gun for producing a hollow cylindrical stream of electrons along an axial path in a predetermined direction comprising: a profile-shaping electrode having a frusto-conical internal surface of revolution concentric about said axial path and diverging in said direction at a predetermined angle, the conical frustum being determined by first and second planes perpendicular to said axial path, said profile-shaping electrode further comprising a second conical surface lying substantially between said first and second planes radially within said frusto-conical surface and converging at said predetermined angle in said predetermined direction, said frusto-conical and said conical surfaces being spaced from each other by a predetermined annular spacing; a cylindrical, annular cathode concentric about said axial path and having an axial short, emitting end segment, said cathode being disposed in the annular spacing between said frusto-conical surface and said conical surface such that said emitting end segment lies between said first and second planes; an accelerating electrode disposed in a plane perpendicular to said axial path and spaced axially from said profile-shaping electrode, said accelerating electrode having an annular opening concentric about said axial path, said annular opening being disposed contiguously to both the inner and the outer surfaces of said hollow electron beam; and means for providing an axial constraining magnetic field throughout the region from said cathode to said accelerating electrode, said accelerating electrode being maintained at a direct current reference potential of zero volts, said cathode being negative with respect thereto and said profile-shaping electrode being positive with respect thereto whereby electrons are emitted from said emitting end segment of said cathode toward said profile-shaping electrode and are constrained by said magnetic field to flow along said axial path in said predetermined direction through a substantial potential free region to said accelerating electrode.

9. A low noise electron gun for providing a cylindrical

75

beam of electrons along an axial path in a predetermined direction comprising: a cylindrical cathode member having an emissive end portion including a planar end and an emissive cylindrical surface adjacent thereto within an axially short emitting segment; a profile-shaping electrode concentric with said cathode disposed between first and second planes which are transverse to said axial path, said first plane lying aft of said emitting segment by .001 to .500 inch, and said second plane lying forward of said emitting segment by .001 to .100 inch and having a frusto-conical internal surface of revolution disposed symmetrically about said axial path at an angle of 20 to 80 degrees thereto extending between said planes having a minimum diameter at said first plane and a maximum diameter at said second plane thereby diverging along said axial path, the end of said frusto-conical surface having said minimum diameter being radially spaced from said cathode by a distance of from .001 to .100 inch; an accelerating electrode comprising a plane transverse to said path spaced from said profile-shaping electrode and having a circular aperture concentric and contiguous about said axial path; and means for providing an axial constraining magnetic field extending throughout the re-

5 gion between said first plane and said accelerating electrode, said cathode being maintained at a direct current reference potential of zero volts, said accelerating electrode being maintained at a direct current potential which is of the order of three volts is positive with respect thereto and said profile-shaping electrode being maintained at a direct current potential which is of the order of six volts positive with respect to said accelerating electrode.
